DESIGN FOR A COMBINED LAVATORY SPOUT AND WASTE HANDLE

Jean O. Reinecke, Chicago, Ill., assignor to Crane
Co., Chicago, Ill., a corporation of Illinois

Application December 8, 1938, Serial No. 81,660

Term of patent 14 years

To all whom it may concern:

Be it known that I, Jean O. Reinecke, a citizen of the United States, residing at Chicago, in the county of Cook and State of Illinois, whose post-office address is 664 North Michigan Avenue, Chicago, Illinois, have invented a new, original, and ornamental Design for a Combined Lavatory Spout and Waste Handle, of which the following is a specification, reference being had to the accompanying drawing, forming part thereof.

Fig. 1 is a top plan view of a combined lavatory spout and waste handle embodying my new design.

Fig. 2 is a side elevation thereof.

Fig. 3 is a front elevation thereof looking toward the outlet of the spout.

I claim:

The ornamental design for a combined lavatory spout and waste handle, substantially as shown.

JEAN O. REINECKE.
